UNITED STATES PATENT OFFICE.

RUFUS LINCOLN EWING, OF McCLEARY, PENNSYLVANIA.

APPARATUS FOR RAISING DOUGH.

SPECIFICATION forming part of Letters Patent No. 367,201, dated July 26, 1887.

Application filed February 17, 1887. Serial No. 227,957. (No model.)

To all whom it may concern:

Be it known that I, RUFUS LINCOLN EWING, a citizen of the United States, residing at McCleary, in the county of Beaver and State of Pennsylvania, have invented certain new and useful Improvements in Apparatus for Raising Dough; and I do hereby declare the following to be a full, clear, and exact description of the invention, such as will enable others skilled in the art to which it appertains to make and use the same, reference being had to the accompanying drawings, and letters of reference marked thereon, which form a part of this specification.

Like letters refer to the same parts throughout the several views.

My invention relates to that class of devices which are adapted for use in raising dough for bakers' use; and it has for its object to generally improve upon apparatus of this class.

To this end, and to such others as the invention may relate, the same consists in the peculiar combinations and in the novel construction, arrangement, and adaptation of parts, all as more fully hereinafter described, shown in the drawings, and then sought to be particularly defined in the claims.

In the accompanying drawings, Figure 1 is a cross-section through an oven constructed in accordance with my invention. Figs. 2 and 3 are detail perspective views of the heater-drum. Fig. 4 is a longitudinal section of the heating-drum.

Referring to the drawings by letter, A represents a suitable cabinet or chest, formed of any suitable material, but preferably of two thicknesses of wood, with the grain of one thickness arranged at right angles to the grain of the other. This greatly increases the strength, and to a considerable extent serves to better retain the heat; but in order to more effectually retain the heat I place between each two thicknesses of wood a layer of heavy felt, paper, or other non-conductor of heat.

Within the chest are arranged a series of two or more removable racks or shelves, B, access to which is had through the doors C. In the lower part of the chest is arranged the heating-drum D, the bottom of which is provided with an aperture, a, to receive the chimney of the lamp, which may be of any approved construction and is placed upon the floor beneath

the chest. Upon the under side of the bottom of this drum I place the guide-strips b, each guide-strip being provided with a flexible partition, b'.

E are dampers, each provided with a suitable handle extending through the side of the chest and having their adjacent ends cut away, as shown, so as to fit around the chimney of the lamp when in place. These dampers are arranged to move in guides or ways formed in the guide-strips, the flexible partitions of which allow of the dampers readily overlapping each other, so as to effectually close the aperture in the bottom of the drum.

The top of the drum is made detachable in any well-known way, and is provided with bolts c c, which pass from the top side thereof downward through the drum and extend through the bottom thereof, their projecting ends being provided with suitable nuts, c', by means of which the top can be brought down tight, in order to overcome the flapping motion of the tin, which, if not obviated, will blow out the lamp when the doors are being closed, the same being caused by the compression of the air within the chamber.

The under side of the top of the drum is provided with a deflector, F, which is permanently attached to the under side of the top of said drum in any suitable manner. It consists, preferably, of a curved piece of metal, (ordinarily tin,) with a piece of iron, d, between the deflector and the top of the drum. This bar d serves to prevent the contact of the deflector with the top of the drum, so that the heat which comes directly from the lamp to this point will not be greater here than elsewhere, the shape of the deflector being calculated to throw the heat toward the back and the bottom of the drum.

G is a V-shaped flange secured to the under side of the top of the drum, the apex of the flange being arranged substantially in the center of the deflector, so that the heat striking the flange, and also that thrown from the deflector, will be conveyed to the outer corners of the drum, thus giving a uniform heat throughout the whole drum. At the rear of the drum a hole, e, is provided, which allows all gases and smoke to pass out, provides ventilation, and causes a draft for the lamp.

Within the chamber or chest A, at any con-

venient point, I arrange a thermometer, H, extending through the top, the state of which will indicate the degree of heat within the chamber. The top A' of the chest A is designed 5 to be of a proper height to form a table suitable for use as a kneading or pastry board.

The joints around the outside of the drum should be cemented or otherwise hermetically closed, so as to render them perfectly tight and 10 prevent the escape of smoke or gas into the chamber above. In use the tray containing the dough is placed upon the lower rack and the doors are closed. The lamp is then lighted and placed in position beneath the drum, with 15 its chimney extending through the aperture in the bottom thereof, and when the required temperature has been secured and the dough has been raised to a proper consistency it is removed and worked into loaves, which are 20 placed within the bread-chamber. After the lamp is removed the dampers are closed, and the heat is thus retained within the chamber. The bread is allowed to remain within the chamber until in readiness for baking.

Having thus described my invention and set 25 forth its merits, what I claim to be new, and desire to secure by Letters Patent, is—

1. The heating-drum provided upon the under side of its top with a curved deflector and a V-shaped flange, with its apex extending to- 30 ward and substantially in the center of said deflector, substantially as and for the purpose specified.

2. The combination, with the drum provided with aperture a, of guide strips b, secured to the under side of said drum and provided with flexible partitions b', and the adjustable dampers E, working in ways formed by said partitions, one upon each side of said aperture, cut away at their inner ends and arranged to over- 40 lap, substantially as described.

In testimony whereof I affix my signature in presence of two witnesses.

RUFUS LINCOLN EWING.
